UNITED STATES PATENT OFFICE.

ROBERT C. DANLY, OF CHICAGO, ILLINOIS.

MAGNETO.

1,200,320.

Specification of Letters Patent.

Patented Oct. 3, 1916.

Application filed February 10, 1915. Serial No. 7,245.

To all whom it may concern:

Be it known that I, ROBERT C. DANLY, a citizen of the United States, residing at Chicago, in the county of Cook, State of Illinois, have invented certain new and useful Improvements in Magnetos, of which the following is a specification.

My invention relates to electric magnetos for use in connection with internal combustion engines, wherein the charge of combustible fluid is ignited by means of an electric spark produced at recurring intervals by means of an electric current generated by a magneto deriving motion from a moving part of the engine mechanism, and suitably connected with the ignition mechanism; the object of my invention being to provide a magneto simple in its construction and generating an electro-motive force to produce a strong current, substantially proof against the displacement of its parts, and operating positively and efficiently for the purpose required.

These objects are attained by means of the mechanism illustrated in the accompanying drawings, in which—

Figure 1 is an end elevation, partly in section, of a magneto having my invention embodied in its construction; Fig. 2 is a side elevation of Fig. 1; Fig. 3 is a top plan view of Fig. 1; Fig. 4 is a detached detail of the mechanism controlling the tripping device; Fig. 5 is an end elevation of a detached part of Fig. 4; and Fig. 6 is a detail illustrating the manner of regulating the operative length of the reciprocating tripping rod that connects the magneto with the engine mechanism.

Referring to the drawings, wherein the same reference numerals designate like parts throughout the several views, the construction of the magneto, including its case 1, removable end wall 2, permanent magnet 3, and armature shaft 4, is substantially the same as that shown and described in my copending application for patent filed April 5, 1914, having Serial No. 829,325.

The magneto is secured to a bracket member 5 by means of bolts 6, the bracket being provided with a laterally turned flange 7 whereby it is secured to the cylinder wall 8 of an internal combustion engine.

9 represents a common form of fixed electrode carried by the flange 7 and extending through the wall 8 into the combustion chamber of the engine, and coöperating with

an oscillating electrode 10 disposed parallel therewith and having an arm 11 at its inner end adapted to intermittently engage with the fixed electrode in a manner to control the electro-motive force of the current of electricity generated by the magneto and produce a spark by the well-known way of make and break contact in the operation of magnetos of the type indicated. Electric current is conducted from the magneto to the fixed electrode by means of the insulated conductor 12 connecting the post 13 of the magneto with a loop member 14 secured to the outside end of the fixed electrode 9. 76

15 represents a magneto actuating bar that is given a reciprocatory movement through suitable connections on one end thereof with a moving part of the engine that is properly timed with the rotary movement of the power shaft and having its opposite end supported by an eccentrically disposed collar 16 secured to one end of a stem member 17 adapted to rock in bearings carried by the bracket member 5, and having secured to its opposite end a toothed index disk 18 that is yieldingly secured in position by means of a plate spring member 19 carried by the bracket 5, and 20 represents a hand piece secured to the disk whereby it may be conveniently manipulated to turn the stem axially in opposite directions as required to raise or lower the bar 15 resting upon the eccentric collar 16, for the purpose of retarding or advancing the spark resulting from the separation of the contact points of the electrodes, as is well understood by those familiar with the art. 85

The bar 15 is made in two parts as illustrated in Fig. 6, one part having a threaded portion 21 that is adjustably received by a central opening in the remaining part 22, and 23 represents a securing nut threaded upon the part 21 and engaging with the adjacent end of the part 22, the associated devices permitting the operative length of the bar to be regulated as conditions may require. 95

24 represents a crank arm secured to the armature shaft 4, and carrying at its free end a stud 25, upon one end of which is journaled one end of a link 26, having its opposite end slidably received by an opening in an ear member 27, preferably integral with the supporting bracket 5, and 28 represents a coiled compression spring carried by the link and operative between the ear 105 110

member 27 and a shoulder portion 29 upon the link in a manner to yieldingly resist a rocking movement of the armature shaft 4 in one direction, and to incline it in an opposite direction through its expansive force when released.

30 represents a lighter buffer spring carried by the extended end of the link beyond the ear 27, and having its force controlled 10 by means of adjusting nuts 31 threaded upon the free end of the link, and 32 represents a supplemental link having one end journaled upon the opposite end of the stud 25, and its opposite end slidably received by 15 an opening in the free end of an arm 33 secured to the outside end of the oscillating electrode 10, the link carrying a compression spring 34 operative between the arm 33 and a shoulder part 35 upon the link in a 20 manner to rock the electrode 10 in a direction to cause engagement of the contact points of the movable and fixed electrodes at proper intervals as governed by the actuating mechanism, and 36 represents an 25 adjustable striker threaded upon the free end of the link and secured in adjusted position by means of a nut 37, and adapted to strike the arm 33 with a hammer stroke and thereby quickly separate the contact points 30 of the electrodes at governed recurring intervals in the operation of the same.

38 represents a rocking saddle member having depending ear members 39 intermediate its opposite ends spaced apart and receiving between them the reciprocating bar 15, to which they are pivotally connected by means of a pin 40. The saddle member is permitted a limited rocking movement upon the pin 40 by means of a compression spring 35 interposed between one end of the saddle and the bar and operative to rock it in a direction to cause it to engage with the end of the link 26 when the bar 15 is moved in one direction, and to slide under it as the bar 40 moves in an opposite direction, as shown in Fig. 1. The opposite ends of the saddle member are formed alike for the purpose of permitting a reversal of its position upon the bar when one of its ends has become so 45 worn through use as to impair its effective operation.

The mechanism as illustrated is designed for use when connected with an internal combustion engine equipped with a charge 55 throttling governor mechanism and wherein the magneto operating bar is given a continuous reciprocatory movement. With the associated parts in assembled relation and the bar 15 properly regulated as to its 60 length to cause the saddle member 38 to engage the link 26 in a manner to oscillate the armature of the magneto through a predetermined degree of angular movement, its movement is directly resisted by the compression spring 28 encircling the link and

disposed in a manner to relieve the armature shaft of any force having a tendency to throw it from a true axial oscillation relative to the pole pieces, as is the result of the action of the opposed tension springs shown 70 in my improved form (Fig. 1) above noted.

I believe that I am the first to employ a compression spring for the purpose indicated, and having shown one form of its adaptation I do not wish that my invention 75 be confined to the specific details as shown, it being understood that many minor changes may be made in the organization, form and proportion of parts without departing from the spirit of the invention. 80

What I claim as my invention, and desire to secure by Letters Patent, is:

1. A magneto including an oscillating armature, means operative to positively turn said armature through a predetermined degree of angular movement in one direction, a compression spring mechanism operative to return said armature to its initial position, and a buffer spring limiting the reactive force of said compression 90 spring. 85

2. A magneto including an oscillating armature carrying shaft, a crank arm secured to said shaft, a link having one end pivotally connected with said arm and its opposite end slidably supported, a compression spring carried by said link and operative to swing said arm in one direction and a buffer spring carried by said link and operative in a manner to cushion a reactive force of said 100 compression spring. 95

3. A magneto including an oscillating armature carrying shaft, a supporting base carrying said magneto, an arm secured to said shaft, a link having one end pivotally connected with the free end of said arm and its opposite end slidably carried by said base, and a compression spring carried by said link and reacting between said base and arm. 110

4. A magneto including an oscillating armature carrying shaft, a bracket member supporting said magneto, an arm secured to said shaft, a link having one end pivotally connected with the free end of said arm and its opposite end slidably received by an opening in said bracket, a compression spring carried by said link and reacting between said arm and bracket, and a buffer spring carried by the free end of said link 115 and operative against said bracket to limit a swinging movement of said arm in one direction. 120

5. A magneto including an oscillating armature carrying shaft, a crank arm secured to said shaft, a link having one end pivotally connected with the free end of said arm and its opposite end slidably supported, a compression spring carried by said link upon one side of its pivotal connection 125 130

with said arm and operative to swing said arm in one direction, and a reciprocatory bar engaging with said link upon the opposite side of its pivotal axis intermittently 5 and operative to swing said arm in an opposite direction.

6. A magneto including an oscillating armature carrying shaft, a crank arm secured to said shaft, a link having one end 10 pivotally connected with the free end of said arm and its opposite end slidably supported, a compression spring carried by said link and operative to swing said arm in one direction, a reciprocatory bar, and a rocking 15 saddle member carried by said bar and intermittently engaging with said link to turn said arm in an opposite direction.

7. A magneto including an oscillating armature carrying shaft, an arm secured to 20 said shaft, a magneto actuating bar, and a reversible rocking saddle member carried by said bar and adapted to engage with said arm.

8. A magneto including an oscillating 25 armature carrying shaft, an arm secured to said shaft, a stud secured to the free end of said arm, a link having one end pivoted upon said stud and its opposite end slidably supported by a fixed part of the structure, a 30 compression spring carried by said link and operative to turn said shaft in one direction, a fixed electrode, an oscillating electrode having a lever arm secured thereto, and a second link having one end slidably connected with said lever arm and its opposite 35 end pivotally connected with said stud.

9. A magneto including an oscillating armature carrying shaft, an arm secured to 40 said shaft, a stud secured to the free end of said arm, a link having one end pivoted upon said stud and its opposite end slidably supported by a fixed part of the structure, a 45 compression spring carried by said link and operative to turn said shaft in one direction, a fixed electrode, an oscillating electrode having a lever arm secured thereto, a second link having one end slidably connected with said lever arm and its opposite end pivotally connected with said stud, and a compression

spring carried by said second link and operative to rock said oscillating electrode in a direction to make contact with said fixed electrode. 50

10. A magneto including an oscillating armature carrying shaft, an arm secured to 55 said shaft, a stud secured to the free end of said arm, a link having one end pivoted upon said stud and its opposite end slidably supported by a fixed part of the structure, a compression spring carried by said link and operative to turn said shaft in one 60 direction, a fixed electrode, an oscillating electrode having a lever arm secured thereto, a second link having one end slidably connected with said lever arm and its opposite end pivotally connected with said stud, a compression spring carried by said second link and operative to rock said oscillating electrode in a direction to make contact with 65 said fixed electrode, and a striker carried by the free end of said link and adapted to engage with said lever arm.

11. A magneto including an oscillating armature carrying shaft, a supporting base carrying said magneto, an arm secured to 75 said shaft, a reciprocatory bar adapted to swing said arm in one direction, and an adjustable eccentrically disposed collar carried by said base and engaging with said bar in a manner to control the degree of a swinging movement of said arm. 80

12. A magneto including an oscillating armature carrying shaft, a supporting base carrying said magneto, an arm secured to said shaft, a reciprocatory bar adapted to 85 swing said arm in one direction, a stem journaled in said base, an eccentric collar secured to one end of said stem and supporting said bar, a toothed index disk secured to the opposite end of said stem whereby said 90 collar may be turned in a manner to control the degree of a swinging movement of said arm, and means for yieldingly securing said disk in any desired position of adjustment.
